UNITED STATES PATENT OFFICE

164,613

ELECTRIC SPACE HEATER

Eric C. Wahlberg, Stamford, and John J. Moughtry, Old Greenwich, Conn., assignors to Electrolux Corporation, Old Greenwich, Conn., a corporation of Delaware

Application September 19, 1950, Serial No. 12,266

Term of patent 14 years

(Cl. D81—10)

To all whom it may concern:

Be it known that we, Eric C. Wahlberg and John J. Moughtry, both citizens of the United States of America, residing at Stamford, Connecticut, and Old Greenwich, Connecticut, respectively, have invented a new, original, and ornamental Design for an Electric Space Heater, of which the following is a specification, reference being had to the accompanying drawings, forming part thereof.

Fig. 1 is a perspective view showing the front, top and one end of an electric space heater in accordance with our new design; and

Fig. 2 is a perspective view showing the rear, bottom and opposite end of the space heater illustrated in Fig. 1.

We claim:

The ornamental design for an electric space heater, as shown.

ERIC C. WAHLBERG.
JOHN J. MOUGHTY.
